UREA DERIVATIVES

Paul J. Stoffel, St. Louis, and David J. Beaver, Richmond Heights, Mo., assignors to Monsanto Chemical Company, St. Louis, Mo., a corporation of Delaware

No Drawing. Application October 29, 1956,
Serial No. 618,718

5 Claims. (Cl. 260—553)

This invention relates to new and useful compounds and to methods of making same.

The new compounds of this invention are of the structure

wherein $\text{X}_n\text{C}_6\text{H}_{5-n}$ is a halogen substituted phenyl radical free of substituents ortho to the $—\text{NH—}$ group, where X is a halogen atom and where n is a whole number from 2 to 3. As illustrative of the new compounds of this invention is the following:

N-(3,4-dichlorophenyl) N'-cyclohexyl N'-(3-chloro-2-but enyl) urea
 N-(3,4-dibromophenyl) N'-cyclohexyl N'-(3-chloro-2-but enyl) urea
 N-(3,5-dichlorophenyl) N'-cyclohexyl N'-(3-chloro-2-but enyl) urea
 N-(3,5-dibromophenyl) N'-cyclohexyl N'-(3-chloro-2-but enyl) urea
 N-(3,4,5-trichlorophenyl) N'-cyclohexyl N'-(3-chloro-2-but enyl) urea
 N-(3,4,5-tribromophenyl) N'-cyclohexyl N'-(3-chloro-2-but enyl) urea

As illustrative of the preparation of the urea derivatives of this invention is the following:

Example I

To a suitable reaction vessel equipped with an agitator is added and mixed approximately 9.4 parts by weight of 3,4-dichlorophenylisocyanate, approximately 9.4 parts by weight of N-(3-chloro-2-but enyl) cyclohexylamine, and approximately 36 parts by weight of diethyl ether. The mass is slowly agitated for about one hour at room temperature, filtered, and the filter cake washed with two 18 parts by weight portions of diethyl ether, and then air dried. The white solid product (approximately 17.5 parts by weight) is N-(3,4-dichlorophenyl) N'-cyclohexyl N'-(3-chloro-2-but enyl) urea, M. P. 160.4—160.8° C.

Example II

Employing the procedure of Example I but employing instead of 3,4-dichlorophenylisocyanate an equal weight of 3,5-dichlorophenylisocyanate there is obtained N-(3,5-dichlorophenyl) N'-cyclohexyl N'-(3-chloro-2-but enyl) urea.

Example III

Employing the procedure of Example I but replacing 3,4-dichlorophenylisocyanate with a chemically equivalent weight of 3,4,5-trichlorophenylisocyanate there is obtained N-(3,4,5-trichlorophenyl) N'-cyclohexyl N'-(3-chloro-2-but enyl) urea.

Example IV

Employing the procedure of Example I but replac-

ing 3,4-dichlorophenylisocyanate with a chemically equivalent weight of 3,4-dibromophenylisocyanate there is obtained N-(3,4-dibromophenyl) N'-cyclohexyl N'-(3-chloro-2-but enyl) urea.

5 In the preparation of the new compounds of this invention other inert solvents than diethyl ether may be employed, e. g. di-isopropyl ether, methylbutyl ether, the liquid alkanes and the like. The reaction temperature employed in preparing the new compounds will 10 depend upon the particular reactants and in general will be between room temperature and the reflux temperature of the system.

The compounds of this invention are particularly useful in controlling bacterial growth, particularly *Micrococcus pyogenes* var. *aureus*. In this regard the urea derivatives of this invention when compounded with a 15 detergent soap (i. e. an alkali metal salt of a higher fatty acid of animal or vegetable origin, such as stearic acid, lauric acid, palmitic acid, oleic acid, linoleic acid, ricinoleic acid, and the like, or mixtures thereof obtained from tallow, lard, cocoanut oil, palm oil, castor oil, olive oil, cottonseed oil, and the like) provide highly useful antiseptic detergent soap compositions.

20 In order to illustrate the activity of the urea derivatives of this invention N-(3,4-dichlorophenyl) N'-cyclohexyl N'-(3-chloro-2-but enyl) urea was incorporated in an alkali metal fatty acid soap, a mixture of sodium and potassium salts of fatty acids whose fatty acid content analyzes

	Percent
Oleic and linoleic acid	About 46
Stearic acid	About 14
Palmitic acid	About 30
Lower fatty acids (myristic, lauric, etc.)	About 10

30 in a weight ratio of one part to 50 parts soap. Aliquots were added to a Sabourard's dextrose agar medium so as to give concentrations in parts per million as set forth below. The agar in each case was then poured 35 into a petri dish, allowed to harden and then inoculated with a standard culture of *Micrococcus pyogenes* var. *aureus* of standard resistance. The incubation in each instance was made at 37° C. for 48 hours. The extent of growth is noted below:

Compound/Concentration, p. p. m.	1,000	100	10
N-(3,4-dichlorophenyl) N'-cyclohexyl N'-(3-chloro-2-but enyl) urea	none	none	none

50 The same control of *Micrococcus pyogenes* var. *aureus* is obtained by replacing N-(3,4-dichlorophenyl) N'-cyclohexyl N'-(3-chloro-2-but enyl) urea in the foregoing detergent soap composition with an equal weight of N-(3,5-dichlorophenyl) N'-cyclohexyl N'-(3-chloro-2-but enyl) urea, N-(3,4-dibromophenyl) N'-cyclohexyl N'-(3-chloro-2-but enyl) urea and N-(3,4,5-trichlorophenyl) N'-cyclohexyl N'-(3-chloro-2-but enyl) urea.

Relatively small amounts of these new urea derivatives 60 in a detergent soap composition have been found to yield effective antiseptic detergent soap compositions. Amounts as low as 0.5 to 1% by weight based on the weight of the detergent soap have proved satisfactory. However, it is preferred to employ these urea derivatives in amounts 65 in the order of 1 to 5% by weight based on the detergent soap. While larger amounts, as for example up to 10% by weight, may be employed the upper limit will be determined by practical considerations. Various colors, antioxidants, perfumes, water softeners, emollients, and 70 the like, may be included where desirable in detergent compositions containing the urea derivatives of this invention. The term "soap" or "detergent soap" as used

herein is employed in its popular or ordinary meaning, i. e. those cleansing compositions prepared from an alkali metal compound such as potassium or sodium hydroxide and a fat or fatty acid, both saturated and unsaturated.

While this invention has been described with respect to certain embodiments it is not so limited and it is to be understood that variations and modifications thereof obvious to those skilled in the art may be made without departing from the spirit or scope of this invention.

What is claimed is:

1. Compounds of the structure

- wherein $\text{X}_n\text{C}_6\text{H}_{5-n}$ is a halogen substituted phenyl radical free of substituents ortho to the nitrogen atom, where X is a halogen atom and where n is a whole number from 2 to 3.
- 10 5. The process of making the compounds of claim 1 which comprises reacting in substantially equimolecular proportions N-(3-chloro-2-butenyl) cyclohexylamine and an isocyanate of the structure $\text{X}_n\text{C}_6\text{H}_{5-n}\text{NCO}$, wherein $\text{X}_n\text{C}_6\text{H}_{5-n}$, X and n have the same significance as in claim 1, in an inert organic solvent at a temperature in the range of room temperature to the reflux temperature of the system.
